PAGE 2

FIG. 2

The side not shown is the same in appearance as the side shown.

The two side panels are symmetrically mirror opposite.

I claim:

The ornamental design for a sofa, substantially as shown and described.
